RAILWAY SIGNALING SYSTEM

Paul H. Crago, Wilkinsburg, Pa., assignor to The Union Switch & Signal Company, Swissvale, Pa., a corporation of Pennsylvania

Original application June 10, 1936, Serial No. 84,498. Divided and this application April 10, 1937, Serial No. 136,118

6 Claims. (Cl. 246—46)

My invention relates to railway signaling systems of the type involving light signals which are approach lighted.

One object of my invention is to provide novel means for causing an approach lighted signal to display a restrictive indication when a train approaches the signal if the filament of the lamp for the signal next in advance becomes burned out or broken.

10 Other objects of my invention will appear as the description proceeds.

The present application is a division of my pending application, Serial No. 84,498, filed on June 10, 1936, for Railway signaling systems.

15 I will describe one form of railway signaling system embodying my invention, and will then point out the novel features thereof in claims.

The accompanying drawing is a diagrammatic view showing one form of signaling system embodying my invention.

Referring to the drawing, the reference characters **1** and **1^a** designate the track rails of a stretch of railway track along which traffic normally moves in the direction indicated by the arrow. These track rails are divided, by means of insulated joints **2**, to form blocks, only one of which, **A—B**, is shown complete in the drawing. Each block is provided with a track circuit comprising a track relay, designated by the reference character **TR**, with a suitable distinguishing exponent, and connected across the rails adjacent one end of the section, and a suitable source of track circuit current, here shown as a track battery **3**, connected across the rails adjacent the other end of the section.

Located adjacent the entrance end of each block is a signal designated by the reference character **S** with an exponent corresponding to the location. Each signal, as here shown, is of the type commonly known as a searchlight signal, and comprises an armature **5** mounted to rotate between an intermediate position to which it is biased, and two extreme positions. Each armature **5** is controlled by an armature winding **6**, and is polarized by the field from a permanent magnet or an electromagnet (not shown) in such manner that when the winding **6** is energized, the armature will rotate to its right-hand or left-hand extreme position according as winding **6** is then supplied with current of normal or reverse polarity, respectively. Attached to each armature **5** to rotate therewith are three colored roundels **G**, **R**, and **Y**, which are arranged to be disposed in the path of a beam of light projected from an associated lamp **L** according as the

armature **5** occupies its right-hand extreme position, its intermediate position, or its left-hand extreme position, respectively. For convenience in illustration, each lamp **L** in the drawing is shown disposed above the associated roundels, but it will be readily understood that in actual practice each lamp will be located directly back of the associated roundel, and will have associated therewith a suitable optical system, not shown, for projecting a beam of light from the lamp. The signals **S** each indicate "proceed", "stop", or "caution" according as the roundel **G**, **R**, or **Y** is in front of the associated lamp **L** when this lamp is lighted. Operatively connected with each armature **5** is a circuit controller comprising two movable contact fingers **7** and **8**. The movable contact finger **7** cooperates with a fixed contact **7^a** to close a contact **7—7^a** when the armature **5** occupies its right-hand extreme position, and with a fixed contact **7^b** to close a contact **7—7^b** when the armature occupies its intermediate position or its left-hand extreme position; while the movable contact finger **8** cooperates with a fixed contact **8^a** to close a contact **8—8^a** when the armature occupies its left-hand extreme position, and with a fixed contact **8^b** to close a contact **8—8^b** when the armature occupies its intermediate or its right-hand extreme position. A signal of the type described is disclosed and claimed in Letters Patent of the United States No. 1,864,224, granted to Wesley B. Wells, on June 21, 1932, for Light signals.

Associated with each signal is a slow-releasing signal repeater relay designated by the reference character **SR** with a suitable distinguishing exponent, an approach lighting relay designated by the reference character **ALR** with a suitable distinguishing exponent, and a slow-releasing light-out relay designated by the reference character **LOR** with a suitable distinguishing exponent. Each light-out relay **LOR** is provided with two windings, one of which, **9**, has a sufficiently high resistance so that when this winding is connected in series with the filament of the lamp **L** of the associated signal in a checking circuit for the lamp presently to be described, the lamp will not become lighted, and the other of which, **10**, has a sufficiently low resistance so that when this winding is connected in series with the filament of the lamp **L** of the associated signal in an energizing circuit for the lamp presently to be described, the lamp will become lighted.

Each signal repeater relay is provided with two energizing circuits which are controlled by the circuit controller of the associated signal.

Referring to relay SR^A , for example, the one energizing circuit for this relay is closed when and only when signal S^A indicates proceed, and passes from terminal X of a suitable source of current not shown in the drawing through contact $7-7^a$ of signal S^A , wires 24 and 25 , and the winding of relay SR^A to terminal O . The other energizing circuit for relay SR^A is closed when and only when signal S^A indicates caution, and passes from terminal X through contact $7-7^b$ of signal S^A , wire 32 , contact $8-8^a$ of signal S^A , wire 25 , and the winding of relay SR^A to terminal O . It will be apparent, therefore, that relay SR^A will be energized when signal S^A occupies either its proceed or its caution position, but will be deenergized when signal S^A occupies its stop position. Relay SR^A is made sufficiently slow releasing so that it will not open its front contacts while signal S^A is moving from its proceed to its caution position, or vice-versa.

The winding 6 of each signal is controlled by the associated track and lightout relays and by the signal repeater relay for the signal next in advance, through the medium of a polarized line circuit which includes the winding of the approach lighting relay for the signal next in advance. Referring to signal S^A , for example, when track relay TR^A and lightout relay LOR^A are both energized, and signal repeater relay SR^B is also energized, the polarized line circuit for winding 6 of signal S^A is closed, and under these conditions, winding 6 is supplied with current of normal polarity, the path of the current being from terminal X through the winding of relay ALR^B , wire 12 , front contact $13-13^a$ of relay SR^B , line wire 14 , front contact 15 of track relay TR^A , wire 16 , front contact 17 of lightout relay LOR^A , wire 18 , winding 6 of signal S^A , wire 19 , front contact 20 of track relay TR^A , line wire 21 , front contact $22-22^a$ of signal repeater relay SR^B , and wire 23 to terminal O . When track relay TR^A and lightout relay LOR^A are both energized and signal repeater relay SR^B is deenergized, the polarized line circuit for winding 6 of signal S^A is again closed, but under these conditions, due to the fact that the back contacts $13-13^b$ and $22-22^b$ of relay SR^B are then closed instead of the front contacts $13-13^a$ and $22-22^a$, winding 6 of signal S^A is supplied with current of reverse polarity over this line circuit. When either track relay TR^A or lightout relay LOR^A is deenergized, the polarized line circuit for winding 6 of signal S^A will, of course, be open.

It will be apparent, therefore, that when track relay TR^A and lightout relay LOR^A are both energized, the mechanism of signal S^A will occupy its proceed or its caution position according as signal repeater relay SR^B is then energized or deenergized, but that, when either track relay TR^A or lightout relay LOR^A is deenergized, the mechanism of signal S^A will occupy its stop position. It will also be apparent that approach lighting relay ALR^B will be energized whenever winding 6 of signal S^A is energized by current of either normal or reverse polarity, but that, when winding 6 of signal S^A is deenergized, approach lighting relay ALR^B will also be deenergized.

Each signal lamp L is provided with an energizing circuit which is controlled by the associated signal repeater and approach lighting relays in such manner that this circuit will become closed when either of these relays becomes deenergized, and which includes the low resistance winding 10 of the associated lightout relay. Each

signal lamp L is also provided with a checking circuit which includes the high resistance winding 9 of the associated lightout relay, and which is closed at all times except when the lamp filament becomes broken or burned out. Referring particularly to lamp L^A of signal S^A , the energizing circuit for this lamp passes from terminal X through the filament of lamp L^A , wires 26 and 27 , back contact 28 of relay SR^A connected in multiple with back contact 29 of relay ALR^A , wire 30 , winding 10 of relay LOR^A , and wire 31 to terminal O . The checking circuit for lamp L^A passes from terminal X through the filament of lamp L^A , wire 26 , resistor R^A , and the winding 9 of lightout relay LOR^A to terminal O . The parts are so proportioned that lamp L^A will become lighted when and only when the energizing circuit for the lamp is closed, but that, relay LOR^A will hold its front contacts closed when either the energizing or the checking circuit for lamp L^A is closed.

It should be pointed out that while, as shown in the drawing, each checking circuit includes a resistance R , this resistance can be omitted if the resistance of the high resistance winding is sufficiently high to prevent the filament of the associated lamp from becoming incandescent while the checking circuit in which the resistance is included is closed and the associated energizing circuit is open. It should also be pointed out that when the energizing circuit for a lamp is closed, the checking circuit is also closed, so that the current which is supplied to the lamp flows through the windings 9 and 10 of the associated lightout relay in parallel. The windings 9 and 10 are so arranged that the fluxes set up in the relay when both of these windings are energized are cumulative.

As shown in the drawing, all parts are in their normal positions, that is to say, all relays are picked up, the winding 6 of each signal is supplied with current of normal polarity, so that the armatures 5 or signals S^A and S^B both occupy their right-hand or proceed positions, and the lamps L^A and L^B are both extinguished.

In explaining the operation of the apparatus as a whole, I will first assume that a train moving in the direction of the arrow traverses the stretch of track shown in the drawing. When the train enters the block in rear of block $A-B$, the shunting of the track relay associated with this block will cause approach lighting relay ALR^A to become deenergized and close its back contact 29 . The closing of this contact will complete the energizing circuit for lamp L^A , and this lamp will therefore become lighted and will cause signal S^A to display a proceed indication.

When the train enters block $A-B$, track relay TR^A will become deenergized, and will interrupt the circuit for winding 6 of signal S^A , thus causing the mechanism of this signal to move to its stop position, and approach lighting relay ALR^B to become deenergized. When signal S^A moves to its stop position, it will interrupt the circuit which was previously closed for signal repeater relay SR^A , and since both circuits for this relay will then be open, this relay will become deenergized. The deenergization of relay SR^A will cause the polarity of the current supplied to the circuit for the winding 6 of the signal for the block to the right of block $A-B$ to become closed, and as a result, as soon as the train moves out of this block, this signal will move to its caution position. The deenergization of relay SR^A will also cause this relay to complete, at its back

contact 28, the energizing circuit for lamp L^A including this contact, so that when the approach lighting relay ALR^A picks up due to the train having passed out of the block to the right of block A—B, signal S^A will continue to display a stop indication. The deenergization of approach lighting relay ALR^B will cause the energizing circuit for lamp L^B of signal S^B to become closed, and this lamp will therefore become lighted, thus causing signal S^B to display a proceed indication.

When the train enters the block to the left of block A—B, track relay TR^B will become de-energized and will cause winding 6 of signal S^B to become deenergized. The deenergization of winding 6 of signal S^B will cause the mechanism of this signal to move to its stop position, which movement, in turn, due to the resultant operation of the associated circuit controller, will de-energize signal repeater relay SR^B . When relay SR^B becomes deenergized, it will reverse the polarity of the current supplied to the circuit for winding 6 of signal S^A , but as long as any part of the train remains in block A—B, the circuit for winding 6 will remain open at the front contacts of track relay TR^A , and signal S^A will continue to display a stop indication. As soon, however, as the train passes completely out of block A—B, the resultant energization of track relay TR^A will complete the circuit for winding 6 of signal S^A , and this signal will then move to its caution position. The movement of signal S^A to its caution position will complete the previously traced circuit for signal repeater relay SR^A including contacts 1—7^b and 8—8^a of the circuit controller of signal S^A , and relay SR^A will then pick up. When this relay picks up, it will interrupt the energizing circuit for lamp L^A , and will cause the winding 6 of the signal for the block to the left of block A—B to be supplied with current of normal polarity, whereupon the mechanism of this signal will move to its proceed position.

When the train leaves the block to the left of block A—B, track relay TR^B will pick up and will cause signal S^B to move to its caution position in the same manner that the picking up of track relay TR^A caused signal S^A to move to its caution position. As soon as signal S^B reaches its caution position, signal repeater relay SR^B will pick up, whereupon signal lamp L^B will become extinguished, and the mechanism for signal S^A will move to its proceed position. When the train passes out of the second block in advance of block A—B, signal S^B will move to its proceed position, and all parts will then be restored to the positions in which they are shown in the drawing.

I will now assume that with the parts in the positions in which they are shown in the drawing, the filament of lamp L^B becomes broken, and that a train subsequently enters the block to the right of point A. When the filament of lamp L^B becomes broken, the checking circuit for this lamp becomes interrupted at the lamp filament, and lightout relay LOR^B therefore becomes de-energized, and opens its front contact 47. The opening of this front contact will deenergize the winding 6 of signal S^B , whereupon the signal mechanism of this signal will move to its stop position. When the mechanism of signal S^B moves to its stop position, signal repeater relay SR^B will become deenergized, and will reverse the polarity of the current supplied to winding 6 of signal S^A , thus causing the mechanism of signal S^A to move to its caution position. As a re-

sult, when the train enters the block to the right of point A and causes approach lighting relay ALR^A to become deenergized and complete the circuit for lamp L^A , signal S^A will indicate caution even though neither of the two blocks in advance of point A is occupied.

If signal S^B occupies its caution position instead of its proceed position when the filament of lamp L^B becomes broken, and a train subsequently enters the block to the right of point A, the operation of the apparatus will be similar in all respects to that just described. It will be seen, therefore, that with a signal system constructed in the manner described, if the filament of a signal lamp becomes broken when the mechanism of the signal in the rear occupies its proceed position, the mechanism of the signal in the rear will immediately move to its caution position, thus insuring that an engineman will not be required to pass a signal which indicates proceed, only to find the signal next in advance dark. Since the operating rules of railroads usually require that a dark signal be obeyed as a stop signal, the arrangement herein disclosed aids in removing the operating hazard of a sudden brake application resulting from an unexpected dark signal.

If the lamp of a signal burns out after it has become lighted due to the presence of a train in the block immediately in rear of the signal, both the checking and energizing circuits for the lamp will become open, and the associated lightout relay will become deenergized, and will thus cause the signal mechanism to move to its stop position. This is desirable because since the operating rules of railroads usually require that a dark signal be obeyed as a stop signal, and since the signal mechanism occupies its stop position, if any light from an extraneous source such, for example, as a locomotive headlight or the sun's rays when the sun is close to the horizon, should enter the signal and be reflected back by the optical assembly of the signal, the resulting phantom indication would be a stop indication. The signal mechanism, after being moved to its stop position in the manner just described, will subsequently remain in its stop position until the burned out lamp is replaced, and the signal next in rear will be prevented from moving to its proceed position, even though traffic conditions in advance are such that the mechanism of this signal would normally assume its proceed position.

Although I have herein shown and described only one form of railway signaling system embodying my invention, it is understood that various changes and modifications may be made therein within the scope of the appended claims without departing from the spirit and scope of my invention.

Having thus described my invention, what I claim is:

1. In combination, a stretch of railway track divided into blocks, a relay associated with each block, each said relay having two windings, a signal for each block controlled by traffic conditions in advance and by the associated relay and including a lamp which at times becomes lighted to cause the signal to display an indication, a constantly closed checking circuit for each lamp including the one winding of the associated relay and effective for energizing the associated relay but not for energizing the associated lamp, and means effective when a train approaches a signal for connecting the other winding of the associated relay in parallel with the one winding 75

to thereby cause the signal lamp to become lighted.

2. In combination, a stretch of railway track divided into blocks, a relay associated with each block, each said relay having a high resistance and a low resistance winding, a signal for each block controlled by traffic conditions in advance and by the associated relay and including a lamp which at times becomes lighted to cause the signal to display an indication, a constantly closed checking circuit for each lamp including the high resistance winding of the associated relay and effective for energizing the associated relay but not for energizing the associated lamp, and means effective when a train approaches, a signal for connecting the low resistance winding of the associated relay in parallel with the high resistance winding to thereby cause the signal lamp to become lighted.

20 3. In combination, a stretch of railway track divided into blocks, a track circuit for each block including a track relay; a signal for each block capable of assuming a proceed, caution, or stop position according as the signal mechanism is supplied with current of normal polarity, reverse polarity or is deenergized, each said signal including a lamp which at times becomes lighted to cause the signal to display an indication; a signal repeater relay controlled by each signal and arranged to be energized at all times except when the signal occupies its stop position, a lightout relay for each signal having two windings, an approach lighting relay for each signal; an energizing circuit for each signal mechanism including a front contact of the associated lightout relay, a front contact of the track relay for the associated block, pole changing contacts of the signal repeater relay for the signal next in advance and the winding of the approach lighting relay for the signal next in advance, the parts being so proportioned that each signal energizing circuit will be supplied with current of normal or reverse polarity according as the signal repeater relay which controls it is picked up or released, and that each approach lighting relay will be picked up whenever the signal energizing circuit in which it is included is closed; a constantly closed checking circuit for each lamp including the one winding of the associated lightout relay and effective for energizing the associated lightout relay but not for energizing the associated lamp, and another circuit for each lamp including the other windings of the associated relay connected in parallel with the one winding of such relay over a back contact of the associated approach lighting relay and a back contact of the associated signal repeater relay in multiple.

4. In combination, a stretch of railway track divided into blocks, a track circuit for each block including a track relay; a signal for each block capable of assuming a proceed, caution, or stop position according as the signal mechanism is supplied with current of normal polarity, reverse polarity or is deenergized, each said signal including a lamp which at times becomes lighted to cause the signal to display an indication; a signal repeater relay controlled by each signal and arranged to be energized at all times except

when the signal occupies its stop position, a lightout relay for each signal having a high resistance and a low resistance winding, an approach lighting relay for each signal; an energizing circuit for each signal mechanism including a front contact of the associated lightout relay, a front contact of the track relay for the associated block, pole changing contacts of the signal repeater relay for the signal next in advance and the winding of the approach lighting relay for the signal next in advance, the parts being so proportioned that each signal energizing circuit will be supplied with current of normal or reverse polarity according as the signal repeater relay which controls it is picked up or released, and that each approach lighting relay will be picked up whenever the signal energizing circuit in which it is included is closed; a constantly closed checking circuit for each lamp including the high resistance winding of the associated lightout relay and effective for energizing the associated lightout relay but not for energizing the associated lamp, and another circuit for each lamp including the low resistance windings of the associated relay connected in parallel with the high resistance winding of such relay over a back contact of the associated approach lighting relay and a back contact of the associated signal repeater relay in multiple.

5. In combination, a stretch of railway track divided into blocks, a two winding relay associated with each block, a signal for each block controlled by the associated relay and by traffic conditions in advance and including a lamp which at times becomes lighted to cause the signal to display an indication, an energizing circuit for each lamp controlled by traffic conditions in rear of the associated signal and including one winding of the associated relay, and a constantly closed checking circuit for the lamp including the other winding of the associated relay.

6. In combination, a stretch of railway track divided into blocks, a signal for governing the entrance of traffic into each block including a winding and a lamp and responsive to reversals in the polarity of the current supplied to the winding, a track circuit for each block including a track relay, a slow-releasing signal repeater relay for each signal energized whenever the winding of the associated signal is energized, a lightout relay for each signal having a low resistance winding and a high resistance winding; a polarized line circuit for each signal including the winding of the signal, a front contact of the associated lightout relay, a front contact of the associated track relay, pole-changing contacts of the signal repeater relay for the signal next in advance and the winding of the approach lighting relay for the signal next in advance, an energizing circuit for each lamp including the low resistance winding of the associated lightout relay and a back contact of the associated signal repeater relay connected in multiple with a back contact of the associated approach lighting relay, and a constantly closed checking circuit for each lamp including the high resistance winding of the associated lightout relay.

PAUL H. CRAGO.
